UNITED STATES PATENT OFFICE.

CHARLES E. SCHIMDT, OF NEW YORK, N. Y.

DESIGN FOR A CAKE-PAN.

SPECIFICATION forming part of Design No. 27,936, dated December 7, 1897.

Application filed October 23, 1897. Serial No. 656,215. Term of patent 7 years.

To all whom it may concern:

Be it known that I, CHARLES E. SCHIMDT, a citizen of the United States, residing at New York, in the county and State of New York, 5 have invented and produced a new and original Design for a Cake-Pan, of which the following is a specification, reference being had to the accompanying drawings, forming part thereof, and in which—
10 Figure 1 is a plan view of a cake-pan embodying my design. Fig. 2 is a vertical sectional view of the same on the line 2 2 of Fig. 1.
The essential feature of my design consists in a cake-pan having a series of corrugations 15 in its bottom, which follow the contour of the sides of the pans, interdental spaces being provided between said corrugations.

In the drawings, *a* represents the pan proper, at the bottom of which is a series of projecting corrugations *b*, which follow the contour 20 of the sides *c* of the pan. Between the corrugations *b* are interdental spaces *d*, the bottom walls of which contain grooves *e*. At the center of the pan is an inwardly-projecting teat *f*.
25

Having described my invention, what I claim, and desire to secure by Letters Patent, is—

The design for a cake-pan, substantially as herein shown and described.

CHARLES E. SCHIMDT.
